UNITED STATES PATENT OFFICE.

WILLIAM E. ELLIOTT, OF GRAND RAPIDS, MICHIGAN.

BUTTON-REMOVING TOOL.

1,271,028.

Specification of Letters Patent. Patented July 2, 1918.

Application filed January 3, 1913. Serial No. 69,867.

To all whom it may concern:

Be it known that I, WILLIAM E. ELLIOTT, a citizen of the United States of America, residing at Grand Rapids, in the county of Kent and State of Michigan, have invented certain new and useful Improvements in Button-Removing Tools; and I do hereby declare the following to be a full, clear, and exact description of the invention, such as will enable others skilled in the art to which it appertains to make and use the same.

This invention relates primarily to a button removing tool, and it is the object and purpose thereof to provide a tool which may be used to cut wire staples or the like which are commonly used in connecting shoe buttons to shoes, or any wire extending close along the surface of or partially embedded in a yielding surface, without in any manner cutting or injuring said surface.

A further object is to insure close action of the opposing cutting edges without the necessity of maintaining a close and accurately fitting pivot to the device, and to prevent injury to the cutting edges by contact with each other, and various other objects as will hereinafter appear.

My device consists essentially of two oppositely moving members pivoted to each other and provided with opposing cutting edges in the same plane, stops to limit the movement of these members toward and away from each other, a pair of stops being arranged at each side of the pivot which will engage as the cutting edges come close together, and thus shift the fulcrum from the pivot, one pair of stops operating as a fulcrum and means to engage the fabric and press the same away from the wire to enable the cutting edges to engage the wire only, and in various features of construction, arrangement and operation, as will more fully appear by reference to the accompanying drawing, in which:

Figure 1 is a side elevation of the tool.

Figs. 2 and 3 show elevations respectively of the two co-acting members of the tool.

Figs. 4 and 5 are respectively end elevations taken from the left of the Figs. 2 and 3; and

Fig. 6 shows the construction used for pivotally connecting the parts of the tool together.

Like reference characters refer to like parts throughout the several views of the drawing.

In the construction of the tool, two identical members are used and pivoted together in opposed positions. These members are formed of steel and a description of one will suffice for both, the reference numbers for the parts in Fig. 3 having "a" added thereto. Each head is provided with a central opening 3 around which is a boss 3^a and when the two parts are placed together the openings therein receive a roller 4 which in turn is loosely mounted on a pin 6 having a head 7. The roller is mounted between the head 7 and a washer 5, the parts of the tool being held together after the end of the pin 6 has been headed as indicated at 8. The central portions 9 and 9^a are pivoted to each other side by side, and each is provided with a handle 1. Each portion is also provided with oppositely projecting sectors 10 and 11. The sector 11 at one radial side has a plain shoulder 13 while its opposite side is formed with a cutting edge 14 for the outer part of its length and then with a shoulder 15 in substantial alignment with the cutting edge 14. Similarly the sector 10 is formed with a similar cutting edge at 16 and a similar shoulder 17 in alignment therewith. The sectors being all in the same plane the cutting edges 14 and 16^a and 14^a and 16 come directly opposite each other and when a wire is introduced between them and the tool operated they will act on directly opposed points on opposite sides of the wire and serve to neatly sever it. A spring 18 is located between the handles 2 and under tension its action is to force the handles apart bringing the shoulders 13 and 13^a together and leaving comparatively narrow slots 19 between parts 10^a and 11 and 11^a and 10, thus preventing attempts to cut too large wires, or opening too wide and thus cutting the shoe or other fabric.

In the use of the tool it is brought adjacent a staple which connects a button to a shoe, or other wire extending close to or partially embedded in, a yieldable fabric and the slot 19 is brought so as to receive the wire and as the tool is forced against the material of the shoe or other yieldable fabric, the sectors force such material ahead of them and away from the wire or staple. Accordingly a staple or wire may be cut without injury whatever to the material of the shoe or other fabric. Furthermore after long usage the sleeve 4 will become worn on its outside and the openings 3 and 3^a enlarged, this tend-

ing to cause a looseness of the pivotal connection of the parts. This will have no effect upon the cutting qualities of the tool however, as the shoulders at 17 and 15^a or, 17^a and 15 will in such case serve as a fulcrum on which the parts may turn and will force the cutting edges of the opposite side in alinement and close action regardless of any looseness of the center pivot.

10 It will also be noted that the shoulders also prevent the cutting edges from too close contact whereby they might injure each other.

I have shown cutting edges at both slots though it is of course apparent that I may 15 eliminate the cutting edges at one side and provide plain shoulders the same as at 13 and 13^a and use such shoulders for the removal of parts of a staple after the wire thereof has been cut. This however, is a more expensive structure requiring two dies for 20 stamping out parts where one is now all that is necessary and the construction shown is preferred, it being possible to remove the parts of a staple by engaging the shoulders 25 at 13^a and 13 therewith as will be readily understood.

I claim:

1. In a device of the character described, the combination of a pair of members arranged 30 side by side and pivotally connected together and also provided with spaced sectors projecting therefrom in the same plane and also having opposing radial cutting edges extending to the periphery of the 35 sectors and also having radial plane surfaces in the plane of the cutting edges and peripheral surfaces to engage a fabric and prevent the cutting edges from cutting the same.

2. In a device of the character described, 40 the combination of a pair of flat members centrally pivoted to each other, each member having two oppositely projecting spaced sectors arranged between the sectors on the other member, and all of the sectors arranged 45 in the same plane, said sectors having opposing cutting edges and opposing plane radial surfaces to limit the approach of said edges to each other and other opposing plane radial surfaces to limit the 50 movement of the cutting edges away from each other.

3. In a device of the class described, the combination of a pair of members arranged side by side and centrally pivoted to each other, each member having two oppositely 55 projecting spaced sectors, the sectors being offset into the same plane and alternately interposed, the opposing radial surfaces of the sectors being provided with only sufficient clearance to admit a wire of predetermined size therebetween and also provided with opposing plane radial surfaces throughout, and one or more pair of said sectors also provided with opposing cutting edges extending to the periphery thereof to sever 65 a wire, and peripheral surfaces at each side of the outer ends of said cutting edges.

4. In a device of the character described, the combination of a pair of central members arranged side by side and pivoted to each 70 other, each member having oppositely projecting spaced sectors positioned between the sectors on the other member, and all of said sectors arranged in the same plane, the peripheries of the sectors forming a substantially circular outline, the sectors also having clearance between their radial surfaces only sufficient to admit a wire of predetermined diameter, and all of said surfaces adapted to engage and stop the relative 80 movement of said sectors, one or more pair of radial surfaces also being provided with opposing cutting edges near the outer angles of the sectors, and opposing stop surfaces in line with said edges and inward therefrom. 85

5. In a device of the character described, a pair of flat members arranged side by side and pivotally connected together, each member having two oppositely projecting sectors arranged in alternate interspaced relation with the sectors of the other member and offset to bring all of the radial surfaces in the same plane, two adjacent sectors being provided with overlapping handle members, the opposing radial surfaces opposite the 95 handles having opposing stop surfaces only, the two other pairs of opposing radial surfaces having opposing cutting edges and opposing stop surfaces, and a spring between the handles. 100

In testimony whereof I affix my signature.
WILLIAM E. ELLIOTT.
